UNITED STATES PATENT OFFICE.

HOWARD D. COLMAN, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS.

WINDER.

Original application filed October 30, 1911, Serial No. 657,529. Renewed February 10, 1916, Serial No. 77,525. Divided and this application filed August 15, 1917. Serial No. 186,286.

To all whom it may concern:

Be it known that I HOWARD D. COLMAN, a citizen of the United States, residing at Rockford, in the county of Winnebago and State of Illinois, have invented certain new and useful Improvements in Winders, of which the following is a specification.

This invention relates to spoolers or winders, and one of the objects of the invention is to provide means for detecting exhaustion of the threads being wound and for throwing the spool or cheese out of operation when the thread running thereto is exhausted.

Another object of the invention is to keep the yarn-traversing means and the periphery of the yarn mass close together during the winding operation.

In the accompanying drawings, Figure 1 is a fragmental side elevation of a winder embodying the features of my invention. Fig. 2 is a fragmental end elevation of one of the winder units. Fig. 3 is a vertical sectional view taken in the plane of dotted line 3 in Fig. 1, showing a thread as being wound upon the thread container. Fig. 4 is a sectional view of the yarn-traversing means. Fig. 5 is a perspective view of said means. Figs. 6 and 7 are fragmental detail views of the cheese arm. Fig. 8 is a view similar to that of Fig. 3, but on a smaller scale, and showing the thread as being exhausted, the throw-out mechanism being about to operate. Fig. 9 illustrates the unit in the thrown-out condition. Fig. 10 represents the operation of a certain locking device.

This application is a division of application Serial No. 657,529, filed October 30, 1911, renewed February 10, 1916, Ser. No. 77,525. (Patent No. 1,239,669, issued Sept. 11, 1917.)

The embodiment herein shown of my invention is a machine for rewinding yarn from a bobbin *a* or *b* (Fig. 2) onto cores *c* to form cheeses *d*. The winding, detecting and throwing-out mechanisms for each cheese will be herein termed a winding unit.

In the present embodiment, the cores or cheeses are rotated through peripheral contact with a roll 2 driven in any suitable manner.

Upon the supporting frame of the machine is a series of brackets 4, each mounted so as to be capable of a slight pivotal movement, for a purpose to appear hereinafter.

In this instance each bracket 4 is provided with a bearing sleeve 5 (Figs. 1 and 3) which is pivotally mounted on a rod 6 the ends of which are supported in brackets 7 fixed to the machine framework. As shown in Fig. 3 the point of pivotal support for each bracket 4 is at one side of its center of gravity, so that the bracket tends to occupy the position represented in said figure.

Each bracket 4 has bearings 8 at its upper end. 9 is a cheese-supporting lever provided upon one side and between its ends with a pivot 10 which is mounted in the bearings 8, said pivot being fast to the lever. At the end of the long arm of the lever 9 is means for rotatably supporting the cheese, which means may be of any suitable character.

The yarn may be traversed back and forth to build up the cheese by any suitable guiding means, as, for example, that fully described in said Patent No. 1,239,669. In the construction shown in said patent, there is fixed in the supporting framework in front of the roll 2 a rail or flange 22 (Figs. 3 and 4). At the rear or inner side of said rail is another rail 23, said rails being secured together by screws 24. Between said rails are clamped plates 25 having inclined or cam edges 28. The cam portions 28 are at the limits of the to-and-fro motion of the yarn. The yarn is moved laterally in one direction by an endless traveling tape 29 having yarn-engaging projections 30 thereon, the yarn being moved in the opposite direction by a similar endless tape 31 having like projections 32. Said tapes travel through guide-ways formed between the rails 22 and 23 and the plates 25. The tapes may be driven by any suitable means.

Fig. 5 represents a projection 32 on the tape 31 as having carried the thread to the right across the periphery of the cheese, the projection being shown as forcing the thread up the inclined or cam surface 28. As soon as the yarn has been carried above the projection, the yarn will of course be free from said projection, and the tension of winding will cause the yarn to spring into or toward a straight line joining the bobbin and the cheese. At this moment a projection 30 upon the tape 29 traveling the opposite direction catches the yarn and moves it toward the left across the periphery of the cheese. After the left-hand traverse has been com-

pleted the yarn is released from the tape 29 by the left-hand cam surface 28, and is then picked up by a projection upon the tape 31, and again moved to the right. The 5 tapes thus alternately pick up the yarn and move it over the periphery of the cheese.

Referring to Fig. 3. It is desirable to keep the yarn-traversing means and the periphery of the cheese close together during the winding operation. For this purpose the bracket 4 is pivotally supported, as hereinbefore described, and a movement of translation is imparted to the lever 9 by means of a stud 45 on the lever arranged to 10 lie against a cam or guide surface 46 on the bracket 7, said guide surface being of such form that as the cheese increases in diameter the center of the cheese will move upwardly in such a path as will cause the 15 periphery of the cheese to remain close to the yarn-traversing means.

The means herein shown for detecting exhaustion of the yarn and for throwing the winding unit out of operation will now be described. To the forward arm 9^a of the lever 9 is pivoted a depending link 47, the lower portion of which may be in the form of an elongated loop, as indicated in Fig. 1. Said link is given a tendency to swing 20 rearwardly by means of a weight 48 attached to an arm 47^a on the link. When the thread exhausts, mechanism to be herein-after described swings the link 47 to a position within reach of a continuously oscillating hook 49 (Fig. 3) which pulls the link 25 downward and thereby throws the lever 9 from the position shown in Fig. 8 to that indicated in Fig. 9, whereby the cheese is withdrawn from the roll and the rotation 30 of the cheese suspended. The hooks 49 are fixed upon a shaft 50 which may be rocked by any suitable means.

Upon reference to Fig. 3 it will be seen that if the bracket 4 were free to swing when 45 the hook 49 acts, the pull of said hook would be mainly expended in an effort to cause pivotal movement of the bracket, which effort would be resisted by the stud 45 bearing against the cam 46. I therefore provide means for locking the bracket 4 against pivotal movement just before the hook 49 acts, which means, in the present embodiment, consists of the following instrumentalities: A bearing bracket 56 is 50 fixed to the lower end of each bracket 4. In said bearing bracket is pivotally mounted a pivot pin 57, upon which is loosely mounted a bell-crank member 58 having a shoe 59 upon one of its arms and an adjustable stop 60 upon its other arm. Said shoe 55 is adapted to make sliding contact with the periphery of an abutment or locking plate 61 fixed upon the shaft 50 adjacent to the hook 49, which plate has a peripheral notch 62 into which the heel 63 of the shoe 59

drops. Fixed to the pivot pin 57 is an arm 64 carrying a pin 65 arranged to be engaged by the link 47 as the latter swings rearwardly. 66 is a stop pin in the bracket 4 to limit forward swinging movement of the arm 64, and 67 is a stop pin in the forward arm of the bell-crank member 58 arranged to be engaged by the arm 64. The weight of the rear portion of the member 58 is slightly greater than that of the forward portion of 70 said member, but the weight of the arm 64 when it rests against the pin 66 is sufficient to overbalance the member 58 and cause it to hang in the position shown in Fig. 3. The operation of these devices is as follows: 80

When the yarn exhausts, the link 47 swings by gravity against the pin 65 and raises the arm 64 into the position indicated in Fig. 8. As soon as the pin 67 is relieved of the weight of the arm 64, the bell-crank member 58 tilts until the heel 63 rests upon the periphery of the locking plate 61. During the next forward swing of said plate, the heel 63 catches in the notch 62, and continuing movement of said plate 90 causes the shoe 59 to make contact with the plate as represented in Fig. 10. Such contact occurs a moment before the hook 49 commences to pull downwardly upon the link 47. If in the growth of the yarn mass 95 the upper portion of the bracket 4 has tilted forward, the engagement of the plate 61 with the shoe 59 causes the upper portion of the bracket to swing rearwardly to a normal position that permits the stud 45 to clear the cam 46. It will be evident that when the shoe 59 lies in contact with the periphery of the plate 61, the bracket 4 cannot swing downwardly upon its pivot 6, and that the downward movement of the 100 link 47 will cause the cheese-carrying lever 9 to swing up and over toward the position shown in Fig. 9.

The hook 49 is represented in its lowest position in Fig. 9. As the hook swings upwardly, the lever 9 swings down to the position shown in said figure, the link 47 bending slightly over a stop pin 68. When the hook 49 has risen sufficiently, the link 110 springs out of the hook into the position 115 indicated in Fig. 9, in which position it is out of the way of the hook.

69 is a bell-crank lever pivoted at 70 in the bracket 4. The arm 69^a of said lever is acted upon by a tension spring 71, while the arm 69^b normally bears against a lug 72 cast integral with or otherwise suitably secured to the pivot 10 of the lever 9. When the winding of the cheese is started, the lug 72 stands at an acute angle to the arm 69^b, the spring 71 being then able to exert sufficient pressure to insure proper driving contact between the core and the roll 2. As the diameter of the cheese increases, the lug 72 turns toward a position at a right 120 angle to the arm 69^b. 125

angle with the arm 69^b, whereby the spring pressure transmitted to the lever 9 decreases. This graduation in pressure is provided, partly, in order that the central portion of the cheese shall be denser than the outer portion, thus counteracting the spreading tendency exerted by the outer layers of yarn on the inner layers. The friction of the arm 69^b against the lug 72 10 also prevents the cheese from bounding and keeps it running in a true circle. It will be seen that the bell-crank lever 69, spring 71 and lug 72 tend to resist movement of the lever 9 away from the rotatory element 2, said means being gradually rendered less effective as the cheese increases in diameter.

When the cheese is thrown out of driving contact with the roll 2, a lug 73 fast 20 on the pivot 10 strikes the arm 69^b, whereby said arm serves yieldingly to arrest the movement of the lever 9 and to determine the thrown-out position of the cheese.

The bobbins may be supported in any 25 preferred manner; herein they are shown as supported in bobbin-holders 74 and 75 (Fig. 2), which are arranged in pairs, the pairs of bobbin holders being fixed upon a rod 76 extending longitudinally of the 30 framework. The two holders of each pair support a bobbin being unwound and a reserve bobbin. For convenience in picking up the end of the yarn on the reserve bobbin, said end may be held in a clamp 77 35 of any suitable construction carried by an arm 78.

In passing from the bobbin to the traverse mechanism, the running thread extends into a operative relation to detector 40 means, which means may be of any preferred form. Herein I have shown two stationary parallel wires 79 and 80 (Figs. 1 and 3) fixed to the bracket 7, each of said wires having an inclined portion 81, 82, respectively, to guide the thread behind the wires when the thread is being placed in running position, as will appear more fully hereinafter. A bail 83 is pivoted at 83^a (Fig. 1) to two adjacent brackets 7 and is 45 provided with a weighted arm 84 and a stop 85 arranged to strike a portion of machine frame (see Fig. 8). The transverse portion of the bail 83 is adapted to lie between the wires 79 and 80, and be supported by the running thread. A portion 50 86 (Figs. 1 and 3) of the bail is adapted to lie behind the portion 87 of the link 47 to hold the link in the position shown in Fig. 3 so long as the thread is running. When 55 the thread exhausts through breakage of the thread or because the thread has been wholly unwound from its bobbin, the weighted arm 84 causes the bail to swing into the position shown in Fig. 8, thereby 60 releasing the link 47, which immediately 65

swings rearwardly into a position within reach of the hook 49, and withdraws the weight of the arm 64 from the bell-crank locking member 58. The latter then locks the bracket 4 against pivotal movement, 70 and the hook 49 throws the cheese out of operation.

The winding unit may be restored to operative condition by an attendant who ties the reserve thread to the thread end 75 on the cheese, the new strand thus formed extending from the reserve bobbin to the cheese and in front of the bail 83. The attendant then swings the lever 9 and the bail 83 into their operative positions. When 80 the lever 9 and the bail 83 are being thus returned to operative position, the new thread is first carried against the guides 81 and 82, and as the winding tension is placed upon the thread it slips down said guides 85 to a position behind the wires 79 and 80. 88 is a stop to limit lateral movement of the yarn in one direction as it passes into running position.

The unit may also be restored to operation 90 by a mechanism (not shown) of any suitable character, arranged to travel along the series of winder units.

In some of the following claims I have, for the sake of brevity, used the term "a 95 winding couple" to indicate two yarn masses, one of which is being rewound onto the other, without regard to the form, size or location of such masses.

I claim as my invention: 100

1. A winder having, in combination, a rotatory element; a pivoted bracket; a lever pivoted to said bracket; means on said lever for rotatably supporting a yarn mass in peripheral contact with said rotatory element; 105 means for supporting a yarn mass to be rewound onto the other yarn mass; yarn guiding means; means for giving said lever a movement of translation as the first mentioned yarn mass increases in diameter to 110 control the position of the latter with reference to said guiding means; means for pivotally moving said lever to withdraw the first mentioned yarn mass from contact with said rotatory element; and means for locking 115 said bracket against movement before said withdrawing means operates.

2. A winder having, in combination, means for supporting a winding couple, said means including a pivoted support; yarn 120 guiding means; means for shifting one member of the couple relative to said guiding means as that member increases in diameter; means for throwing the couple out of operation; and means for locking said pivoted support against movement before the throwing-out means acts.

3. A winder having, in combination, means for supporting a winding couple, said means including a pivoted support; yarn 130

guiding means; means for shifting one member of the couple relative to said guiding means as that member increases in diameter; means for throwing the couple out of operation, said throwing-out means including a swinging link; and means operated by said link for locking said pivoted support against movement.

4. A winder having, in combination, 10 a rotatory element; a bracket; a lever pivoted to said bracket; means on said lever for rotatably supporting a yarn mass in peripheral contact with said rotatory element; means for supporting a yarn mass to be rewound 15 onto the other yarn mass; yarn guiding means; means for giving said lever a movement of translation as the first mentioned yarn mass increases in diameter whereby to position the latter so that its periphery is 20 maintained in substantial proximity to said guiding means; and means for pivotally moving said lever to withdraw the first mentioned yarn mass from contact with said rotatory element.

5. A winder having, in combination, a 25 rotatory element; a pivoted bracket; a lever pivoted to said bracket; means on said lever for rotatably supporting a yarn mass in peripheral contact with said rotatory element; 30 means for supporting a yarn mass to be rewound onto the other yarn mass; yarn guiding means; means for giving said lever a movement of translation and thereby shifting the position of the first mentioned yarn 35 mass relative to said guiding means as it increases in diameter; means for pivotally moving said lever to remove the first mentioned yarn mass from contact with said rotatory element; an abutment; and a member 40 arranged to be interposed between the bracket and the abutment to prevent pivotal movement of the latter.

6. A winder having, in combination, a 45 rotatory element; a pivoted bracket; a lever pivoted to said bracket; means on said lever for rotatably supporting a yarn mass in peripheral contact with said rotatory element; means for supporting a yarn mass to be rewound onto the other yarn mass; means for 50 giving said lever a movement of translation as the first mentioned yarn mass increases in diameter whereby to control the position of the latter relative to that of the running thread; means for pivotally moving said lever to remove the first mentioned yarn mass from contact with said rotatory element; an oscillatory abutment; and a shoe 55 pivoted to said bracket and adapted to lie in contact with said abutment to prevent pivotal movement of the bracket.

7. A winder having, in combination, a 60 rotatory element; a pivoted bracket; a lever pivoted to said bracket; means on said lever for rotatably supporting a yarn mass in peripheral contact with said rotatory element;

means for supporting a yarn mass to be rewound onto the other yarn mass; means for giving said lever a movement of translation as the first mentioned yarn mass increases in diameter whereby to control the 70 position of the latter relative to that of the running thread; a link connected to said lever; a hook adapted to engage said link to pivotally move the lever to withdraw the first mentioned yarn mass from contact with 75 said rotatory element; and means operable by said link for locking said bracket against pivotal movement before said hook operates.

8. A winder having, in combination, a 80 rotatory element; a bracket pivoted so as to tend to swing away from said element; a lever pivoted on said bracket and arranged to support a yarn mass in peripheral contact with said element; yarn-traversing means located in operative relation to the 85 path of the running thread; and means to cause movement of said bracket so as to maintain the periphery of the yarn mass adjacent the yarn traversing means as the 90 yarn mass increases in diameter.

9. A winder having, in combination, a 95 rotatory element; a movable support; a lever pivoted to such support and adapted to support a yarn mass in peripheral contact with said rotatory element; yarn-traversing 100 means located in operative relation to the path of the running thread; and means engaging said lever to cause movement of the support so as to maintain the periphery of the 105 yarn mass adjacent to the yarn-traversing 110 means as the yarn mass increases in diameter.

10. A winder having, in combination, a 115 rotatory element; a pivoted bracket; a lever pivoted to said bracket; means on said lever for rotatably supporting a yarn mass in 120 peripheral contact with said rotatory element; means for supporting a yarn mass to be rewound onto the other yarn mass; a stationary cam member between the bracket 110 and said element; and means on the lever to engage said cam member whereby to effect the movement of the first mentioned yarn mass to maintain its periphery in proper relation to the running thread.

11. A winder having, in combination, a 125 roll for rotating a yarn mass through peripheral contact therewith, a movable support, a member pivotally mounted on said support for rotatably supporting the yarn 130 mass for movement toward and away from the roll, a device to traverse the yarn, and means for moving said support so as to impart a movement of translation to said member in a direction to main the yarn mass and the traversing device in proximity to each other as the winding proceeds.

12. A winder having, in combination, a 135 rotatory element; a movable support; a lever pivoted to such support and adapted to sup-

- port a yarn mass in peripheral contact with said rotatory element; yarn-traversing means located in operative relation to the path of the running thread; and cam means 5 engaging said lever to cause translatory movement of the lever as the yarn mass increases in diameter and thereby to maintain the periphery of the yarn mass in proximity to the yarn traversing means.
- 10 13. A winder having, in combination, a rotatory element; a bracket pivoted so as to tend to swing away from said element; a lever pivoted on said bracket and arranged to support a yarn mass in peripheral contact with said element; yarn-traversing means located in operative relation to the path of the running thread; a stationary cam member between the bracket and said element; and a stud on said lever arranged 15 to lie in contact with said cam member.
14. A winder having, in combination, a rotatory element; a pivoted bracket; a lever pivoted to said bracket; means on said lever for rotatably supporting a yarn mass in peripheral contact with said rotatory element; means for controlling pivotal movement of the bracket in one direction; means for pivotally moving said lever to withdraw the 20 yarn mass from contact with said rotatory element; and means for swinging said bracket to a normal position before said throwing-out means operates.
15. A winder having, in combination, a rotatory element; a pivoted bracket; a lever pivoted to said bracket; means on said lever for rotatably supporting a yarn mass in peripheral contact with said rotatory element; means for supporting a yarn mass to be rewound onto the other yarn mass; means for 25 controlling the pivotal movement of the bracket in one direction; means for pivotally moving said lever to withdraw the first mentioned yarn mass from contact with said rotatory element; and means for swinging
- said bracket to a normal position before said throwing-out means operates. 45
16. A winder having, in combination, a pivoted bracket; means for controlling the pivotal movement of the bracket in one direction as the winding progresses whereby to control the position of the yarn mass to maintain its periphery in proper relation to the running thread; an abutment; and a member arranged to be interposed between the bracket and the abutment to prevent 50 pivotal movement of the bracket. 55
17. In a winder, the combination with a thread-guiding device, of a stationary upright guide member, a support pivotally mounted so as to swing normally away from said guide member, and means mounted upon said support rotatably supporting a yarn mass with its periphery initially adjacent said thread guiding device, said supporting means for the yarn mass having an operative engagement with said guide member and said guide member serving as the 60 yarn mass increases in diameter to move its supporting means whereby to maintain the 70 periphery of the yarn mass at all times in close proximity to the thread guiding device. 65
18. In a winder, the combination of a rotatory element, a guiding device for yarn 75 mounted adjacent said rotatory element, a pivotal support for a yarn mass, means operable to move said support during the winding operation so as to maintain the periphery of the yarn mass in close proximity 80 to the guiding device, and means tending to resist the movement of said pivotal support away from said rotatory element, said means being gradually rendered less effective as the yarn mass increases in diameter. 85
- In testimony whereof, I have hereunto set my hand.

HOWARD D. COLMAN.
